CLAIM

The ornamental design for a combined disposable toothbrush and cap, as shown and described.

DESCRIPTION

FIG. 1 is an exploded perspective view of a combined disposable toothbrush and cap showing my new design; FIG. 2 is a front elevational view thereof with the cap in place on the toothbrush;

FIG. 3 is a rear elevational view of FIG. 2;

FIG. 4 is a side elevational view of FIG. 2, the opposite side being a mirror image;

FIG. 5 is a top plan view of FIG. 2; and,

FIG. 6 is a bottom plan view of FIG. 2.

FIG. 4.

FIG. 2

FIG. 3.

FIG. 5.

FIG. 6.
